UNITED STATES PATENT OFFICE.

WILLIAM J. NEWMAN, OF CHICAGO, ILLINOIS.

FLOAT FOR AUTOTRUCKS.

1,289,880.

Specification of Letters Patent. Patented Dec. 31, 1918.

Application filed April 25, 1918. Serial No. 230,670.

To all whom it may concern:

Be it known that I, WILLIAM J. NEWMAN, a citizen of the United States, residing at Chicago, in the county of Cook and State of Illinois, have invented certain new and useful Improvements in Floats for Autotrucks, of which the following is a specification.

While modern auto trucks are capable of hauling relatively large loads, say from five, to ten tons, they are wholly inefficient and impractical unless provided with a suitable roadway over which to travel. I use such trucks for excavating basements or cellars and transferring the excavated material to dumps. Of course, there is no permanent roadway in such basement, and there is usually more or less distance from the roadway to the dump which cannot be traversed by the trucks under ordinary conditions.

In order to provide a roadway for such trucks under the conditions mentioned, or wherever there is soft or bad ground, I provide floats which comprise the present invention.

The objects of this invention are to provide floats or devices which may be utilized for building temporary roadways for auto trucks; to provide floats or devices which may be readily moved, preferably by two men; to provide floats or devices for making temporary roadways which may be reversed so that either side can be used; and in general to provide the improved temporary roadway or track construction which will be more fully described hereinafter.

In the accompanying drawings illustrating this invention:

Figure 1 is a side view of a roadway formed with my improved floats, with a truck shown thereon;

Fig. 2 is a plan view of the roadway; and, Fig. 3 is a perspective view of one of the floats or roadway units.

In accordance with this invention, I provide a plurality of floats which are made sufficiently strong so as to withstand the heavy loads passing thereover, but which are preferably made of convenient size so that they can be readily handled by two men. These floats are usually placed in alignment in two rows which are spaced so that the centers of the floats will correspond with the tread of the trucks.

As shown in the drawings, 4 represents a float made in accordance with my invention. 55 This float is constructed of a number of transverse planks or boards 5 forming the top thereof, and longitudinal boards 6 forming the bottom thereof. In the floats which I use, the upper members are usually made 60 of 2"x8" planks and the lower members are made of 3"x10" planks. These members are securely bolted together by bolts 7 or otherwise fastened together by rivets or any other well known means so as to make a 65 solid and substantial platform.

These floats may be provided with any suitable handles for convenience in carrying the same, but I prefer to insert or fasten rods 8 in the ends, as shown in Fig. 3, and 70 cut away the end members to form recesses 9 so that the workmen may grasp the rods 8 or may use hand-hooks 10 for lifting the same.

It will be noted that these recesses are 75 relatively small and will not interfere with the truck wheels passing over the floats. The rods 8, being located in a central plane, are in position to be engaged when the float has either side up.

These floats are usually made about three feet wide and three or four feet long and are arranged in rows, as shown in Fig. 2, to make a track or roadway for the trucks.

It will be readily seen that the adjacent members may be tied or fastened together, but in actual practice I have found that this is unnecessary as the trucks tend to press the floats together. It will be noted that the transverse planks form excellent surfaces 90 for the truck wheels, and, on account of the rigid construction, these will last for a considerable length of time. After the top members have become worn, the floats may be reversed and the bottom members used 95 for the surface of the roadway, in which case they are preferably turned so that the planks will lie transversely of the roadway.

The use of these floats will be apparent to those familiar with heavy trucking work. I have found them exceedingly useful in bridging soft spots in the road and in making temporary roadways in various places where heavy trucks could not otherwise be used. After the floats have served their 105 purpose in one location, they may be readily

carried by two men and transferred to other locations or loaded to be carried for use in other places.

It will be observed that changes may be made in the details of construction of these floats without departing from the scope of this invention, and therefore, I do not wish to be limited to the exact construction herein shown and described, except as specified 10 in the following claims, in which I claim:

1. A float for forming a roadway for auto trucks, comprising a series of transverse members superimposed on a series of longitudinal members and secured thereto to 15 form an unyielding support, the ends of said float having recesses formed therein, and bars inserted in said recesses.

2. A float of the character set forth comprising a plurality of upper and lower tim-

bers secured together to form an unyielding 20 rectangular support, and handles for lifting said support.

3. A temporary roadway for auto trucks comprising a plurality of floats, each float consisting of a series of transverse and 25 longitudinal timbers secured together to form rectangular supporting units, with handles at each end thereof.

4. A float for auto trucks comprising a series of transverse planks arranged adjacent to each other, and superimposed on a series of longitudinal planks arranged adjacent to each other, and means for fastening the planks together to form a unitary structure of such dimensions as to be readily 35 carried by two men.

WILLIAM J. NEWMAN.
